[57] CLAIM

The ornamental design for a storage case for diskettes, substantially as shown and described.

DESCRIPTION

FIG. 1 is a perspective view of a storage case for diskettes showing our new design, with the case closed; FIG. 2 is the same perspective view thereof with the case fully opened;

FIG. 3 is a top plan view thereof;

FIG. 4 is a right side elevational view thereof;

FIG. 5 is a front elevational view thereof; and

FIG. 6 is a rear elevational view thereof.

FIG. 1

FIG. 2

FIG. 3

FIG. 4

FIG. 5

FIG. 6
